UNITED STATES PATENT OFFICE.

HARRY C. STICKEL, OF STAR JUNCTION, PENNSYLVANIA.

CAR-TRUCK

1,011,518.

Specification of Letters Patent. Patented Dec. 12. 1911.

Application filed April 19, 1911. Serial No. 622,151.

To all whom it may concern:

Be it known that I, HARRY C. STICKEL, a citizen of the United States, residing at Star Junction, in the county of Fayette and State of Pennsylvania, have invented a new and useful Car-Truck, of which the following is a specification.

The invention relates to improvements in car trucks.

10 Heretofore when the springs of a car truck become weakened and permit the bolster to sink and cause the car coupling to drop below its normal position and interfere with the proper coupling of the cars, it has 15 been the practice to interpose a board between the springs and the bolster for elevating the latter.

The object of the present invention is to improve the construction of car trucks, and 20 to provide a simple, strong and efficient car truck of comparatively inexpensive construction, equipped with means for enabling the springs and the bolster to be readily adjusted in a vertical direction to hold the 25 same at the proper elevation to maintain the car coupling at the standard height.

In the drawings:—Figure 1 is a side elevation of a car truck, constructed in accordance with this invention. Fig. 2 is a plan view of a portion of the same. Fig. 3 is a vertical sectional view on the line 3—3 of Fig. 2. Fig. 4 is a similar view on the line 4—4 of Fig. 2. Fig. 5 is a vertical sectional view on the line 5—5 of Fig. 2. Fig. 6 is a 35 horizontal sectional view on the line 6—6 of Fig. 1. Fig. 7 is a detail sectional view on the line 7—7 of Fig. 1. Fig. 8 is a detail perspective view of the spring plank. Fig. 9 is a detail perspective view of the bolster 40 retaining plate.

Like numerals of reference designate corresponding parts in all the figures of the drawings.

In the accompanying drawings in which 45 is illustrated the preferred embodiment of the invention, 1 designates a side frame, constructed of cast metal, or other suitable material and provided with a central bolster receiving opening 2 and having vertical 50 column guides 3 at opposite sides of the opening. The truck bolster 4 is interlocked with the column guides by means of opposite recesses 5, which are of sufficient size to permit the necessary swing or play of the

bolster. The bolster may be of any preferred construction, and the central opening 2 of the side frame 1 is enlarged at the top at opposite sides at 6, the extensions or enlargements 6 of the opening being located above the column guides, and adapted to 55 permit the bolster to be introduced into the opening 2 and slidably engaged with the column guides 3. The bolster is retained in its interlocked relation with the column guides by means of the top plate 7, fitted in and 60 conforming to the configuration of the enlarged top portion of the opening 2 and provided at its outer face with a marginal flange 8, extending along the top and around the ends of the bolster confining 65 plate and fitted in a corresponding recess 9 of the side frame, as clearly shown in Fig. 6 of the drawings, whereby the bolster confining plate is arranged in flush relation with the side frame. The bolster confining plate is also provided with spaced transverse ribs 10, fitting in transverse grooves 11 in the top wall of the opening 2 and projecting from the inner face of the side frame and provided with registering 70 perforations 12 for the reception of a key 75 13, or other suitable fastening device, whereby the bolster confining plate is detachably locked in the enlarged top portion of the opening 2. By this construction, the bolster is securely confined in its interlocked 80 relation with the side frames of the truck.

The bolster is supported by coiled springs 14, which may be of any preferred construction. The springs 14, which are preferably 90 arranged in pairs, are seated upon the end of a spring plank 15, provided with upwardly extending longitudinal side flanges 16 and seated upon an adjustable bottom plate 17. The bottom plate, 95 which is adapted to be adjusted by screws 18, is provided at its ends with recesses 19, receiving the guide columns 3, whereby the bottom plate is slidably interlocked with the same. The screws 18, which are mounted in threaded openings 20 in the bottom wall or sill 21 of the opening 2, have reduced upper portions 22, which extend into registering openings 23 and 24 of the spring plank and the adjustable plate. The screws 100 present supporting shoulders 25 to the adjustable plate and have lower squared ends 26, adapted to be engaged by a wrench or

- other suitable tool, whereby the screws may be adjusted, should it become necessary to raise the springs and the bolster to maintain the car coupling at the standard height.
- 5 This adjustment will obviate the inconvenience of interposing a board between the bolster and the springs, which has heretofore been necessary to raise the bolster and the car coupling to the proper height.
- 10 The side frames are provided at their ends with upper and lower horizontal arms 27 and 28 to receive standard journal boxes 29, which are secured in place by bolts 30. Filler plates 31 of either wood or metal being preferably interposed between the lower arms 28 and the journal boxes 29. The filler plates are adapted to be removed so as to afford sufficient space between the arms to permit the journal boxes to be readily removed and replaced. The bolts 30 pierce the filler plates and retain the same in place.

The side frames are provided at their inner faces with hollow integral studs 32, located at opposite sides of the opening 2 at 25 the top thereof and forming seats for pins from which the vertical beams are suspended.

Having thus fully described my invention, what I claim as new and desire to secure by Letters Patent, is:—

30 1. A car truck including side frames provided with openings, a truck bolster having its ends arranged in the openings of the side frames, springs supporting the bolster, and adjusting means mounted on the side frames at the bottom of the openings for raising the springs and the bolster.

2. A car truck including side frames provided with openings, a bolster, a spring 40 plank, springs mounted on the spring plank and supporting the bolster, adjustable plates slidably interlocked with the side frames and arranged beneath the spring plank, and means for raising the adjustable plates.

45 3. A car truck including side frames provided with openings, a bolster, a spring plank, springs mounted on the spring plank and supporting the bolster, adjustable plates slidably interlocked with the side frames 50 and arranged beneath the spring plank, and adjusting screws mounted in the threaded openings of the side frames and arranged to engage the adjustable plates and having operating portions located beneath the side frames.

55 4. A car truck including side frames provided with openings, a bolster, a spring plank, springs mounted on the spring plank and supporting the bolster, adjustable plates 60 slidably interlocked with the side frames and arranged beneath the spring plank, said plates and spring plank being provided with registering openings, and adjusting screws mounted in threaded openings in the bottom 65 of the side frames and having reduced por-

tions fitting in the openings of the plates and the spring plank and forming shoulders arranged to support the said plates.

5. A car truck including side frames provided at a point between the top and bottom with openings enlarged at the top portion and having column guides at opposite sides below the enlarged top portions of the openings, a truck bolster provided at its ends with opposite recesses receiving the column guides, whereby the bolster is slidably interlocked with the side frames, the said enlarged top portions of the openings permitting the bolster to be engaged with and disengaged from the column guides, springs supporting the bolster, and plates detachably secured beneath and fitting against the under side of the top of the side frames and filling the enlarged top portions of the said openings and confining the bolster within the same.

6. A car truck including side frames provided at a point between the top and bottom with openings enlarged at the top portion and having column guides at opposite sides below the enlarged top portions of the openings, a truck bolster provided at its ends with opposite recesses receiving the column guides, whereby the bolster is slidably interlocked with the side frames, the said enlarged top portions of the openings permitting the bolster to be engaged with and disengaged from the column guides, springs supporting the bolster, and plates fitting 90 beneath the top portions of the side frames and filling the enlarged top portions of the said openings and provided at the outer faces of the side frames with flanges engaging the outer faces of the top portions of said frames, and means carried by the plates and detachably engaging the inner faces of the top portions of the side frames for retaining the plates in the enlarged portions of the openings.

7. A car truck including side frames provided with openings and having column guides at opposite sides of the same, said openings being enlarged above the column guides and being provided in their top walls with transverse grooves, a bolster provided at its ends with recesses receiving the column guides, whereby the bolster is slidably interlocked with the side frames, the enlarged top portions of the openings permitting the bolster to be engaged with and disengaged 110 from the column guides, springs supporting the bolster, plates fitting in and filling the enlarged top portions of the said openings and provided at the outer faces of the side frames with flanges and having transverse 115 ribs extending through the said grooves to the inner faces of the side frames, and removable fastening devices piercing the ribs and engaging the side frames at the inner faces thereof.

8. In a car truck, the combination with side frames provided at their ends with integral upper and lower arms, removable filler plates arranged upon the upper faces
5 of the lower arms, journal boxes seated upon the filler plates, and bolts piercing the arms and the filler plates and retaining the journal boxes in place.

In testimony, that I claim the foregoing as my own, I have hereto affixed my signature in the presence of two witnesses. 10
